(57) CLAIM

The ornamental design for a lid, as shown and described.

DESCRIPTION

FIG. 1 is a front-top perspective view of a lid showing my new design.

FIG. 2 is a front-bottom perspective thereof.

FIG. 3 is a front elevational view thereof.

FIG. 4 is a right side elevational view thereof.

FIG. 5 is a top plan view thereof.

FIG. 6 is a left side elevational view thereof.

FIG. 7 is a rear elevational view thereof; and,

FIG. 8 is a bottom plan view thereof.

Stippling and tangency lines in the drawings represent the three-dimensional contours of the design, and are not intended to indicate surface decoration.
